AUTOMATIC BOBBIN UNWINDING DEVICE

Walter Schweiter, Horgen, Switzerland, assignor to Schweiter Ltd., Horgen, Switzerland, a corporation of Switzerland

Application July 27, 1949, Serial No. 107,027
In Switzerland July 31, 1948

9 Claims. (Cl. 242—36)

1

When yarn is being wound off spinning and doubling tubes or bobbins the undesirable condition is observed frequently that the last few coils of the yarn on the bobbins are soiled and in part the winding is not correct because a portion of the coils are wound in a loose condition. It is desirable therefore not to work up this residual yarn, but by scanning to interrupt the process of unwinding each bobbin before the bobbin is completely empty and replace the bobbin by a new one. Scanning meets with difficulties, however, in that the spinning and doubling bobbins of different makes have different external diameters, differences which may amount for instance to two or three millimeters. Controlling the interruption of the unwinding operations by mere scanning of the residual yarn is therefore too inaccurate, since a yarn residue of two to three millimeters in winding thickness produces too much waste. According to the present invention the unwinding of bobbins is interrupted, or discontinued, independently of the diameter of the empty bobbins.

To this end two feeler members are used for scanning. One of these feeler members scans the uncovered body of the bobbin and the other scans the coils being unwound. A member of the apparatus which unwinds the bobbins is made subject to the relative positions of the two feeler members as it were, and as these come to a certain relative position, this member acts to stop the unwinding. These relative positions are so selected that the unwinding is interrupted, or stopped, before the last few coils are unwound from the bobbin.

In the accompanying drawing the foregoing is illustrated in connection with a known type of unwinding apparatus. In the drawing—

Fig. 1 is a side elevation of the device, only one bobbin, and that partly unwound, being shown; however;

Fig. 2 is a view in plan of the device of Fig. 1;
Fig. 3 is a front elevation thereof;

Fig. 4 shows the positions which the feelers occupy with bobbins of two different diameters; and both filled; looking upwards toward the feelers and the bottoms of the bobbins as it were;

Fig. 5 is a side elevation of the feelers and a bobbin; and

Fig. 6 shows another form of feeler heads.

In Figs. 1, 2 and 3, the gear box or casing **1** contains mechanism, say of a known kind, to rotate the bobbin-carrying plate **2** step-by-step. The plate **2**, constituting a magazine for bobbins, carries pegs **3** on each of which a bobbin **4** can be

placed for unwinding. The mechanism within the box **1** includes an escapement device which, whenever activated, causes the mechanism to turn the plate **2** one step, a distance equal to the distance between two adjacent pegs **3**, and thus bring the bobbins on the pegs **3** to the unwinding station one at a time. Power to rotate the plate **2** is furnished by the continuously rotating shaft **5** which is driven by a pulley **7**. A small rotation of the shaft **5** in a clockwise direction (Fig. 1) releases the escapement and thus causes the plate **2** to turn one step, i. e. the distance between two adjacent bobbins. As before indicated, such mechanisms, including the escapement, are well known and therefore need not be described in detail.

Adjacent the unwinding station, a pivot **8** is rigidly fastened to the top of the gearbox **1**, and on this pivot is pivoted the feeler **9** which scans the uncovered portion of each bobbin **4** at the unwinding station. This feeler **9** has the form of a double-arm lever. The lever arm **9a** of the feeler **9** is subjected to the tension of the spring **10**, Figs. 1 and 4, which is secured to the bracket **11** fastened to the gearbox **1**, so that the opposite lever arm **9b**, acting as the feeler per se, presses against the uncovered lower portion of the bobbin when the latter is in its unwinding position, Figs. 3 and 5. At the extremity of the lever arm **9a** a pivot **12** is mounted on which the second feeler **13**, in the form of a one-armed feeler lever **13**, can rotate freely, the two feelers thereby being in engagement with each other. This one-armed feeler lever **13** is drawn by a spring **13a**, attached to **13** and to **9a**, toward the pivot **8** and in action rests lightly and resiliently on the coils **14** of the bobbin **4** which is being unwound at the moment. A pivot **15** also is secured to the gearbox **1** and on this a two-armed lever **16** is pivotally mounted which serves to control the operation of the mechanism of the gear case **1** in response to the relative positions of the two feelers **9** and **13**. A hardened pin or stud **17** is fitted in the upper end **16a** of the lever **16** to engage the coil feeler **13**, this stud or pin being provided with a feeler-engaging tip **18** tapered to a point or line at angles of, say, approximately 45 degrees. The lower end of the lever **16** is provided with a hardened angular end **16b**, and the part of the lever that is below pivot **15** is heavier than the part of it that is above the pivot, so that the tip **18** tends to press against the feeler lever **13**. A lever **21** secured to the control shaft **5** is drawn upward by a spring **22** hooked round the stud **23** on the gear box. A locking rod **24**,

provided at one end with a screw thread 25 and at the other with a hardened end 26 having a shoulder 27, is so mounted in the lever 21 as to be slideable longitudinally of the lever 21. By means of spring 28 and the threaded nut 29, the locking rod 24 can be displaced longitudinally, i. e. so adjusted that the end 16b of lever 16 can slide earlier or later off the end 26. The thickness of the residue of yarn to be left on the bobbin is determinable by this adjustment. Projecting laterally from the lever 21 is a pillar bolt 30 on which the roller 31 is mounted. An eccentric disc 32, with, for example, two eccentric bosses 33, is keyed on to the drive shaft 6, said disc so acting on the roller 31 when rotating that each eccentric boss momentarily depresses the end portion 26 from the knife-edge 16b so that the pin 17 can follow the movement of the feeler lever 13 unobstructedly.

Fig. 6 shows an alternative form of the pin 17 and the feeler lever 13. In which form, the face 17b of the pin 17a is broad, and may be flat, while the feeler lever 13b, which serves the same purpose as the feeler 13, has a semicircular boss 13c. The purpose of the two shapes of contact surface of the pins 17 and 17a respectively is described later.

The operation of the device in scanning bobbins will be seen from Fig. 4. The feeler member 9 is rotatable on the pivot 8 and its arm 9b is pressed by the spring 10 against the uncovered portion 4a (Figs. 3 and 5) of the bobbin 4, said portion being indicated by the circle 37 in Fig. 4. The feeler member 13 is pivotally mounted on the pivot 12 on the lever 9, being drawn by the spring 13a toward the bobbin. The free end of the feeler member 13 thus rests on the winding 14 of the bobbin, indicated by the circle 36 in Fig. 4, when the bobbin is in its unwinding position. If now a thicker tube, for instance, with the uncovered diameter of the circle 38, is used, then the lever 9b of the feeler member 9 rests on uncovered portion of the bobbin as before, while the feeler member 13 as before bears on the winding indicated by the circle 39. Because of the larger diameter 38 of the uncovered end of the bobbin however, the feeler member 9 takes a new position, i. e. it occupies the position shown by a dot-dash line in Fig. 4, and the feeler 13 is shifted with it. The tip 18 of the stop pin 17 always moves along the dash-dot line 42 in Fig. 4 however, as the winding 14 (36 or 39) is unwound, namely in the direction of the center of the pivot 8. Because of its tapered end, the action of the tip 18 of the pin 17 is not interfered with by the rotation of the feelers, and the same result is achieved by the boss 13c of Fig. 6. When a bobbin is completely unwound, the feeler 13 will, of course, occupy some certain position with respect to the feeler 9; the particular position will depend on the construction of the parts; for example, the feeler may stand over the center of the post 8. The feeler 13 will occupy substantially this particular position, with a completely unwound bobbin, regardless of whether the external diameter of the unwound bobbin is large or small. Accordingly a given residue of yarn on a bobbin will hold the feeler spaced a certain distance from this particular position, and the distance will be substantially the same regardless of whether the residue is on a bobbin of large diameter or on one of small diameter. As will be described hereunder, this distance serves the purpose of shutting off the unwinding process.

A bobbin is being unwound at position A in

Fig. 2. The feeler lever 9b is pressed by the spring 10 against the uncovered portion 4a of the bobbin 4 as shown in Figs. 4 and 5, while at the same time the feeler member 13 is pressed against the wound portion 14 of the bobbin 4. Since the feeler member 13 is pivoted, and pivoted in relation to the feeler lever 9b, the tip 18 of the pin 17 on the lever 16 is free to move in the direction of the line 42 in Fig. 4. Initially, i. e. while a bobbin at A is completely filled, the lower end 16b of the lever 16 stands well within range of the end 26 of lever 21, with the result that the lever 21 cannot tip upwards. As the eccentric bosses 33 press down the roller 31 and with it the lever 21 at brief intervals however, the pawl 16 is freed at intervals to turn on its pivot 15, and since the lower end of the pawl 16 is heavier, the position and travel of the lever end 16b is determined by the position and travel of the lever 13. I. e., as the unwinding of the bobbin 4 proceeds, the feeler member 13 moves from the tip 18, and at each depression of the lever end 26 from the end 16b of lever 16, caused by the eccentric boss 33, the tip 18 follows the lever 13. The adjustment of the rod 24, by nut 29 and spring 28, is such however that when the winding 14 is unwound down to, say, the last one or two coils, the end 16b of lever 16 no longer bears against the end 26 of lever 21, so that the spring 22 can pull the lever 21 upwards. This rotates the shaft 5 through a small angle and thus interrupts the process of unwinding from bobbin 4 on the post A, and causes the rotation of the plate 2 by the distance between two spindles, i. e. from A to B, thus bringing a new bobbin to unwinding position. By means of the regulating nut 29, the size of the residue of yarn remaining on the bobbin 4 can be adjusted, since by means of said nut the end 26 of lever 21 can be advanced or retracted and will therefore permit the end 16b of lever 16 to slide off it at an earlier or a later moment.

It will be understood that my invention is not limited to the details of operation and construction described above and illustrated in the accompanying drawing except as appears hereafter in the claims, and that these claims are intended to include equivalents of the elements recited in them as well as those elements themselves.

I claim:

1. In mechanism for bobbin unwinding, two feelers, one of said feelers being located to scan an uncovered portion of a bobbin being unwound and the other of said feelers being located to scan coils on the bobbin, and one of said feelers being in engagement with the other to affect the action of the latter, and a controller connected and responsive to said feelers to stop the unwinding operation.

2. The subject matter of claim 1 characterized by the fact that said mechanism includes a magazine for bobbins and bobbin-advancing mechanism to advance filled bobbins of said magazine to unwinding position seriatim, and said controller is connected to said bobbin-advancing mechanism to control the same.

3. The subject matter of claim 1 characterized by the fact that the controller engages and responds to the said feeler which scans coils on the bobbin.

4. In mechanism for bobbin unwinding, two feelers, one of said feelers being located to scan an uncovered portion of the bobbin being unwound and the other of said feelers being located

to scan coils on the bobbin, and one of said feelers being mounted and movable on the other feeler to be positioned by the latter relative to the bobbin, and a controller responsive to said feelers to stop the unwinding operation.

5. The subject matter of claim 4, characterized by the fact that the feeler which scans the coils is the feeler which is mounted and movable on the other feeler.

6. The subject matter of claim 4, characterized by the fact that the feeler which scans the uncovered portion of the bobbin is a pivoted feeler and is pivoted at a fixed place, and the feeler which scans the coils is a pivoted feeler and is pivoted on the feeler which scans an uncovered portion of the bobbin so as to be displaced as the latter feeler turns on its pivot.

7. The combination of mechanism for bobbin-unwinding having a member movable to stop the unwinding operations, a feeler pivoted at a fixed place to scan an uncovered portion of a bobbin being unwound, a feeler pivoted on the first mentioned feeler to scan coils on the bobbin, said feelers being located to scan simultaneously the coils and uncovered portion of a bobbin, and a

10

25

controller connected to the second mentioned feeler and movable therewith from the path of said movable member.

8. The combination of the subject matter of claim 7 with mechanism to intermittently withdraw said movable member from contact with said controller to permit the controller to move freely under the control of the second mentioned feeler.

9. The subject matter of claim 8, characterized by the fact that said movable member is a lever and said mechanism is an eccentric type mechanism to act on said lever.
